NOVELTY ANKLET SOCK

Olon J. Robertson, Pilot Mountain, N.C., assignor to Pilot Hosiery Mills, Inc., Pilot Mountain, N.C., a corporation of North Carolina

Application July 27, 1955, Serial No. 524,754

7 Claims. (Cl. 66—178)

The present invention relates to seamless knit socks and more particularly to novelty anklet socks in which an auxiliary cuff cooperates with a folded leg portion to form a covered pouch or pocket.

Recently it has become the vogue in informal attire for young ladies to wear anklet socks or half hose that may be rolled or turned down in order to form a bulbous or folded area at the top of the anklet. Very often within the folds of the anklet portion of a sock various articles such as, coins, keys, lipstick, etc. may be carried rather inconspicuously.

An object of the present invention is to provide an anklet sock with a covered and guarded pouch formed integrally in the knitted sock.

Another object of the present invention is the provision of a double-ply cuff formed intermediate the leg portion of an anklet sock which cuff may be concealed by a foldable leg portion.

Still a further object of the present invention is to provide a novelty anklet sock having formed therein a concealable pouch integrally knit intermediate the leg portion of the anklet so that articles may be placed in the pouch and concealed therein by folding the free leg portion thereover.

Other and further objects and many of the attendant advantages of this novelty sock will become readily apparent from the following detailed description taken in connection with the accompanying drawings in which like characters of reference designate corresponding parts throughout the several views and wherein:

Fig. 1 is a side elevational view illustrating the present invention with a cuff portion intermediate the leg portion and in the normal upturned position to form a pouch adjacent to the extended leg portion;

Fig. 2 is a partial side elevational view illustrating the sock of Fig. 1 with the upper leg portion folded over the cuff portion;

Fig. 3 is a partial longitudinal sectional view taken substantially along the plane of line 3—3 of Fig. 2 and illustrates the relationship of the folded leg portion adjacent to the cuff portion;

Fig. 4 is an enlarged fragmentary view taken substantially along the plane of line 4—4 of Fig. 1 to illustrate the relationship of the double-ply cuff portion adjacent to the top section of the leg portion.

Referring to the drawings and particularly to Fig. 1, there is shown an embodiment of the present invention which consists of a seamless knit anklet sock 10 having a foot portion 11 with toe and heel pockets 12 and 13, respectively, a leg portion 14 with top and bottom sections 15 and 16, respectively, and an uplifted cuff portion 17. The anklet sock is knit integrally throughout by a continuous knitting operation on a conventional circular knitting machine.

In a preferred embodiment of the invention the foot portion 11 and the bottom section 16 of the leg portion 14 may be plain knit. The remainder of the stocking is preferably rib knit in order to provide greater elasticity

2

or resilience to the upper portions of the sock, that is, the cuff and top section 15, so that the anklet will fit snugly to the contour of the wearer's ankle.

At the ankle or boot section of the sock there is a juncture line 19 above which the rib knitting may take place. Above this line is formed the double-ply cuff portion 17 which consists of an outer ply 20 that is knit continuously and integrally with the bottom section 16 and then the knitted cuff is folded back on itself to form an inner ply 21. Plain or plain needle loops of the inner ply 21 may then be transferred to needles which retained loops 28 to which loops the top section 15 will be knit.

The top section 15 of the leg portion is then knit to the desired length which length may reach vertically at least sufficiently above the top folded edge 22 of the cuff to envelope or cover the entire outer ply 20 of the cuff portion when the top section is folded thereover. It is preferred however, that the vertically reaching top section of the leg portion 14 extend sufficiently above the top fold 22 of the cuff so that a double-roll or fold may be provided. The top edge 23 of the sock may be concealed when the top section 15 of the leg portion is of sufficient length so as to extend above the top edge 23 by substantially twice the length of the cuff length in order that the top edge 23 of the sock may be hidden since it will be positioned contiguous with the top and outer ply 20 of the cuff, as is clearly illustrated in Fig. 3.

With the inner ply of the cuff portion placed upwardly against the top section 15 of the leg portion 14 a pouch or pocket 24 is formed therebetween and the folded leg portion provides a cover to enclose the pouch. The leg portion also tends to urge the outer ply 20 of the cuff against the wearer's leg preventing the cuff from falling down during walking or running.

In Fig. 4 a fragmentary section of a fabric structure illustrates a formation of the double-ply cuff 17 as it may be integrally knit to the leg portion. The loops in courses 26 and 27 are continuously knit in the bottom section 16 and continue to form the cuff 17, however, spaced needles (not shown) on the machine retain the loops 28 on the needle shanks while the cuff portion is being knit. The retained loops are then cast off upon completion of the cuff when the knitting of the top section of the leg is continued. The elongated loops 28 represent the retained loops and indicate the continuation of the leg portion. As will be readily apparent from Fig. 4, the loops omitted between the elongated loops 28 constitute the connecting loops for the offset cuff portion displaced from the plane of the leg portion. Fig. 4 shows the continuity of the knitted cuff with the leg portion and the cuff securing elongated loops 28. In the finished sock the inner ply 21 is directly knit into the leg portion 14 so that upon severance of the elongated loops 28 the entire leg portion may be extended linearly. In the fully extended condition the cuff length will be incorporated into the leg portion length. When in this fully extended condition the entire leg portion may be continuously rolled or folded to form a large rolled anklet sock top.

Obviously there are many modifications and variations that may be made in the spacing and the number of loops between the continuously knit cuff and the top section of the leg portion as well as various novelty loops and sock lengths that may be employed in view of the above teachings without departing from the real spirit and purpose of the present invention. It is therefore to be understood that within the scope of the appended claims many modified forms of the novelty anklet sock may be made and therefore modifications are contemplated.

70 What is claimed is:

1. A novelty seamless knit anklet sock of the char-

acter described comprising a plain knit foot portion, a leg portion having a top and a bottom section, and a double-ply cuff portion at the boot of said leg portion and integrally knit in the leg portion intermediate the top and bottom sections of the leg portion, said cuff portion lying contiguous to the leg portion in the cuff upright position, the top of the leg portion extending at least once the length of the vertical reach of the cuff above the top of the cuff portion.

2. A novelty seamless knit anklet sock of the character described having a top leg portion adapted to be turned down on itself and a cuff at the boot of said leg portion and integrally knit and continuous with the leg portion folded on itself to form a double ply, said top leg portion extending over said cuff to at least partially conceal the cuff and forming a covered pouch between the cuff and the leg portion.

3. A seamless knit anklet sock of the character described including a foot portion and a continuously knit leg portion having top and bottom sections, a cuff portion integrally knit with and formed intermediate the top and bottom sections and folded upon itself to lie contiguous to the top section of the leg portion, said top section being adapted to be folded down to conceal the cuff portion forming a covered pouch.

4. A seamless knit anklet sock of the character described having a plain knit foot portion, a leg portion having continuously knit top and bottom sections, said bottom section at least being of plain knit construction, a cuff portion integrally knit with and formed intermediate the top and bottom sections, said cuff being folded upon itself and knit to the top section, said top section reaching above the cuff portion in the cuff upturned position and adapted to be folded on itself whereby the cuff is covered by the folded top to form a concealed and covered pouch.

5. A seamless knit anklet sock of the character de-

scribed having a plain knit foot portion, a leg portion continuously knit the foot portion and having top and bottom sections, a cuff portion integrally knit into the leg portion at the juncture between the top and bottom sections and folded on itself to form a double ply, said top section extending for a length sufficient to conceal the cuff portion when folded thereover whereby a concealed pouch is formed between the top section and the cuff portion.

6. A novelty seamless knit anklet sock of the character described comprising a plain knit foot portion, a leg portion having a top and a bottom portion, and a double ply cuff portion at the boot of said leg portion and intermediate the top and bottom of the leg portion, said cuff portion lying contiguous to the leg portion in the cuff upright position, the top of the leg portion extending at least once the length of the vertical reach of the cuff above the top of the cuff.

7. A seamless knit anklet stocking of the character described including a foot portion and a continuously knit leg portion having top and bottom sections, a knit cuff portion intermediate the top and bottom sections and folded upon itself to lie contiguous to the top section of the leg portion, said top section being adapted to be folded down to conceal the cuff portion forming a covered pouch.
